(57) **CLAIM**

We claim the ornamental design for an inflatable cat float, as shown and described.

DESCRIPTION

FIG. 1 is a perspective view of an inflatable cat float;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear side elevational view thereof.

The broken lines in FIGS. 1-7 represent portions of the inflatable cat float that form no part of the claimed design.
